SAFETY TIMING SWITCH

Albert L. Judson, Portland, Oreg., assignor to
Iron Fireman Manufacturing Company, Port-
land, Oreg.

Application July 13, 1950, Serial No. 173,616

9 Claims. (Cl. 200—123)

1

This application is a continuation-in-part of application S. N. 20,008, filed April 9, 1948, jointly by Lewis L. Cunningham and Albert L. Judson on an Oil Burner Primary Control, which application issued as Patent Number 2,581,636 on January 8, 1952.

This invention relates generally to thermally actuated electric switches and more particularly to thermally actuated electric switches of the type found useful in Oil Burner Primary Controls for measuring out a limiting time interval during which it is safe to inject oil into the furnace before proper ignition is assured.

To be reliable in time measurement such switches, which rely on an increase of temperature of a bimetal member due to the heat emitted by a fixed resistor through which electric current is passed at a predetermined rate, must be compensated for ambient temperature changes.

It is a common practice in this art to provide a device of this general type having two substantially parallel, spaced bimetal elements of approximately the same active length and similarly influenced by ambient temperature, with each of the elements having a fixed and a free end and with a bridging member hinged to the free end of one of the elements and resting on the free end of the other bimetal element and wherein the bridging member will be released to open a switch when one of the bimetals is heated to a temperature by an electric heater.

It is a principal object of the present invention to provide an improvement in this general type of switch in which the compensating bimetal blade has no structural duty in the switch operating mechanism other than its compensating duty of positioning the bridging member with respect to the other bimetal blade.

How this and other objects are attained will be made clear by reference to the following specification referring to the attached drawings in which

Fig. 1 is a view in perspective of the essential elements of one form of my device with the switching bridge member in switch closed position.

Fig. 2 is similar to Fig. 1 but with the switching bridge member in switch open position.

Fig. 3 is perspective view in partial section taken along the line 3—3 of Fig. 1.

Fig. 4 is a vertical section along the line 4—4 of Fig. 1.

Fig. 5 is a perspective view in partial section of a second form of my device.

Fig. 6 is a perspective view of the adjustment frame of the device of Fig. 5.

Fig. 7 is a plan view of the switch opening strut of the device of Fig. 5.

Fig. 8 is side elevation of the device of Fig. 5 with the elements in the switch open position.

2

Fig. 9 is the same as Fig. 8 but with the elements shown in position at the time of resetting the device after the switch has been tripped as in Fig. 8.

Fig. 10 is a sectional view taken along the line 10—10 of Fig. 8.

Referring now to Figs. 1 to 4 of the drawings, arched bronze leaf spring 20 is supported at its upper end by machine screw 21 threaded into insulating base member 22 and has secured to its downwardly extending end, by machine bolt 23, bimetal element 24 and electric resistor 25 insulated from spring 20 by fiber insulating strip 26. Due to the arched formation of the upper end of spring 20 the lower end of bimetal 24 is moved to the left by tightening screw 21 or to the right by loosening screw 21.

Secured to stationary brass bracket 27 by screw 28 and spacer 29 are bronze spring 30 and bimetal 31. Insulating strip 32 has its right hand end biased upwardly by spring leaf 30 to which it is secured by conducting rivet 33 which in the position shown in Fig. 1 makes electrical contact with conducting rivet 34 securing stiff metal conducting bridge member 35 to bronze leaf spring 36 having its right hand end secured to strip 32 by hollow rivet 37. Spring 36 biases the left hand end of bridge 35 downwardly as shown in Fig. 2 when the right hand end of bridge 35 is unlatched from bimetal 24 as bimetal 24 is warped to the right under the influence of heat emitted from resistor 25 as current is passed therethrough. Double headed loose rivet 38 secured to bridge 35 and T-headed pin 39 limit the movement of bridge 35 with respect to strip 32.

Reset knob 40 secured to crank shaft 41 by pin 42 is used to rotate crank arm 43 downwardly against stop 44 formed on enclosing cover 45 in which shaft 41 is journalled as shown in Fig. 3. Wire spring 46 secured at one end to stationary member 47 biases crank arm 43 upwardly against stop 48 formed on cover 45. Rotating knob 40 to the right causes crank bar 49 to move the right hand end of bridge member 35 downwardly to its reset position as latched on to the end of bimetal 24 as shown in Fig. 1. When arm 43 is in its upper position against stop 48 rod 49 forms a stop limiting the upward travel of bridge 35 when it is unlatched from bimetal 24.

Tang 50 formed on the lower end of compensating bimetal 31 fits loosely into slot 51 formed into strip 32. The right hand end of slot 51 presses lightly against tang 50 due to a slight leftward bias of spring 30. Shoulders 52 on bimetal 31 limit the upward motion of strip 32 in the position shown in Fig. 2.

Bimetals 24 and 31 warp in the same direction on a temperature change and therefore bridge 35 and the lower ends of bimetals 24 and 31 will

maintain their relative positions when influenced only by the ambient temperature. But when current passes from wire 53 through bracket 27 spring 30, rivets 33, 34, bridge 35, bimetal 24, resistor 25, and wire 54, bimetal 24 is heated by resistor 25 and will warp to the right unlatching bridge 35 and breaking the electric circuit between bimetal 24 and bridge 35 as well as between rivets 33 and 34.

Figs. 5 to 10 inclusive illustrate another form of my invention in which bracket 60 secured to insulating base 61 by rivets 62 carries through insulated rivets 63 an electric resistor 64 insulated from bracket 60 by fiber strips 65, and energizable through wires 66 and 67.

Insulatingly spaced by fiber blocks 66 as shown and carrying switch contacts 69 and 70 respectively are bronze leaf spring blades 71 and 72 secured to base 61 by screws 73 threaded into plate 74. Blades 71 and 72 bias contacts 69, 70 towards their closed contact position. Rigid conducting terminal member 75 also forms a stop limiting the movement of blade 71 toward blade 72. Blade 72 extends downwardly as shown terminating at terminal screw 76.

Riveted to plate 74 and adjusting frame 77, compensating bimetal 78 hingedly biases frame 77 in a clockwise direction. Frame 77 is positioned by adjusting screw 78 journaled loosely in base 61 and threaded into frame 77.

Strained between frame 77 and stiff bridge member 79 coil spring 80 biases bridge member 79 to rotate in a counterclockwise direction about its lower end rockably engaged with one end of frame strut 81. The other end of strut 81 is rockably pivoted on frame 77. The free end of compensating bimetal 78 rests against the lower edge of a slot formed in frame strut 81 as shown and gently resists the counterclockwise biasing action of spring 80 on strut 81 with respect to frame 77.

Switch opening strut 82 is made of insulating material and has a single step shouldered reduced portion at one end resting in a slot formed in bridge 79 and limiting the counterclockwise rotation of bridge 79. At its other end strut 82 is first reduced in width and shouldered to pass a limited distance through a slot formed in base 61 and a second slot formed in switch blade 72 as shown in Fig. 7. After passing through base 61 and blade 72, strut 82 is again reduced and shouldered with its second reduced portion passing through a slot formed in blade 71 and with its second shoulder setting a minimum spread between bridge 79 and blade 71. It is seen, as in Fig. 5, that if the free end of bridge 79 is latched or the free end of bimetal 83 riveted to bracket 60, the biasing action of switch blade 71 will push strut 82 to the right for enough to allow contacts 69 and 70 to close but if bimetal 83 warps upwardly enough to allow bridge 79 to be unlatched therefrom then spring 80 through bridge 79 and strut 82 will push blade 72 to the left and open contacts 69, 70. The switch opening action of strut 82 is limited by its shoulder formed where the strut is reduced in width to pass through base 61.

Resetting strut 84 also made of insulating material is guided at its full width towards one end in slot 85 formed in frame 77 and at its other end is shouldered and reduced in width to pass through and be guided in a slot formed in base 61 as shown. The shoulder thus formed coacting with base 61 limits the movement of strut 84 to the left. The reduced portion of strut 84 is

notched on its opposite edges as shown at 86 to receive the bifurcated end of switch blade 72 which being of spring material biasing its contact end to the neutral position shown in Fig. 8 5 locates strut 84 in its endwise position unless acted on by outside forces. Thus should bridge 79 be unlatched from bimetal 83 and switch contacts 69 and 70 be opened as shown in Fig. 8, and after bi-metal 83 has cooled, it is desired to 10 reset the device, the left end of strut 84 can be pushed to the right until blade 72 contacts base 61 which would be the limit of motion to the right for strut 84. In this position the end of bridge 79 would be well beyond the end of bimetal 83 which would take up its unstressed 15 position as in Fig. 9. During this resetting operation it is seen that blade 72 is held completely out of reach of blade 71 so that there is no possibility of holding switch contacts 69, 70 in 20 closed position by manipulation of resetting strut 84. A careful examination of the drawing will show that switch contacts 69, 70 can only be in closed position when bridge 79 is latched or bimetal 83 and resetting strut 84 are positioned by 25 blade 72 which in its neutral position will allow contacts 69-70 to close when bridge 79 allows blade 71 to push strut 82 to the right.

In the form of the device shown in Figs. 5 to 10 the switch and operating resistor can be 30 connected in series after the manner of wiring shown in Figs. 1 and 2, or the energizing resistor can be connected to one circuit through wires 66 and 67 and the switch can be connected into another circuit through terminals 75 and 76.

Having thus completely disclosed and fully 35 described two forms of my improved safety switch in which one of the two active bimetal members has no function except to negate the influence of the ambient temperature on the relative position of the bridge and the other bimetal, I claim:

1. In a primary control for an oil burner, a safety timing switch comprising a first bimetal member, a second bimetal member, an electric heater and a switching member, said safety timing 40 switch being of the type in which the timing period is determined by the influence of an electrical heater on a first bimetal member to open said switch and in which a second bi-metal member is used to compensate said switch for the influence of the ambient temperature on said first bi-metal member, and in which a switching member bridges the temperature positioned ends of said two bi-metal members, the improvement 45 wherein said bridging member is supported by an additional resilient biasing member and wherein said bridging member is located with respect to said first bi-metal member by said second bi-metal member against which said bridging member is biased by said biasing member.

2. In a primary control for an oil burner, a safety timing switching means comprising a first bi-metal element, a second bi-metal element, means bridging the free ends of said first and second bi-metal elements, a support, means for 50 adjustably fixing one end of said first bi-metal to said support, means for fixing one end of said second bi-metal element to said support, means independent of said bi-metal elements for rockably carrying said bridging means on said support, means for biasing said bridging means longitudinally against the free end of said first bi-metal element, means for biasing said bridging means against the free end of said second bi-metal element whereby the position of said bridging 55 means with respect to said first bi-metal ele-

ment is influenced by said second bi-metal element.

3. In a primary control for an oil burner, a safety timing means comprising a support, a first bi-metal element having one end adjustably fixed to said support, a second bi-metal element having one end fixed to said support, a bridging means, means flexibly carrying said bridging means on said support and resilient means adapted to bias said bridging means against the free end of one of said bi-metal elements in its temperature responsive direction and against the free end of the other of said bi-metal elements in a direction perpendicular to its temperature responsive direction.

4. A thermostatic time switch comprising in combination, a first bi-metallic blade fixed at one end to a support and free at the other end, a second bi-metallic blade fixed at one end to said support and free at the other, said blades being adapted to warp in the same direction on a change in ambient temperature, a third blade rockably carried on said support in substantial parallelism with one of said bi-metallic blades, means operably connecting the freely rockable end of said third blade with the free end of said second blade for movement therewith, a lever fulcrumed on said freely rockable end of said third blade, means rotatably biasing one end of said lever against the free end of said first blade in the direction of the fixed end of said first blade, a normally closed electric circuit opening means, means adapted to raise the temperature of one of said bi-metallic blades a substantial amount above the ambient temperature in a fixed time period, whereby said first blade will release said lever at the end of said period, and means whereby said circuit opening means is moved to open circuit position when said lever is released by said first blade.

5. The device of claim 4 including a screw connection between said first blade and said support for adjusting the position of the free end of said first blade with respect to the free end of said second blade.

6. The device of claim 4 including a manually operable push rod adapted to engage said lever for returning said lever to its latched position on said first blade after having been released therefrom.

7. The device of claim 6 including means formed on said push rod adapted to engage said circuit opening means for maintaining said circuit opening means in open circuit position during the manipulation of said manual means.

8. A thermostatic time switch comprising in combination, a first bi-metallic blade fixed at one end and free at the other end, a second bi-metallic blade fixed at one end and free at the other end, said blades being so arranged that their free ends move in the same direction on temperature variations to which they are similarly subjected, a third blade rockable in substantial parallelism with said second bi-metallic blade, means operably connecting said third blade with said second bi-metallic blade for movement therewith, a latching means pivotally carried at one end on said rockable blade and normally latched on the free end of said first bi-metallic blade, an electric heater for one of said blades causing it to warp in a direction to release said latch, and a pair of electric switch contacts normally biased to closed position and adapted to be moved to open position on the release of said latch.
9. A thermostatic switch comprising in combination, first and second bi-metallic blades fixed at one end and free at the other, a rockable blade, a latching means pivotally carried at one end on said rockable blade and normally latching on the free end of said first bi-metallic blade, means operably connecting said latching means with the free end of said second bi-metallic blade whereby a lateral movement of said second bi-metallic blade will cause an equivalent longitudinal movement of said latching means, means for causing one of said bi-metallic blades to move away from the other of said bi-metallic blades whereby said latch will be released from its latched position on the free end of said first bi-metallic blade, a pair of electric switch contacts biased to a closed contact position, and means operatively connecting said latching means and said switch contacts whereby when said latch is released from the end of said first bi-metallic blade said contacts will be separated.
